UNITED STATES PATENT OFFICE.

HARRY V. DRESBACH AND WILLIAM O. DRESBACH, OF JOPLIN, MISSOURI.

OIL-BURNER.

1,115,414.

Specification of Letters Patent.

Patented Oct. 27, 1914.

Application filed July 10, 1914. Serial No. 850,187.

To all whom it may concern:

Be it known that we, HARRY V. DRESBACH and WILLIAM O. DRESBACH, citizens of the United States, residing at Joplin, in the county of Jasper and State of Missouri, have invented certain new and useful Improvements in Oil-Burners, of which the following is a specification.

Our invention relates to an improved burner adapted to operate with kerosene oil or the like as a fuel, and has for an important object the provision of such a device whereby the combustion of the fuel is perfect to a high degree.

15 The invention further aims to provide a burner of the above mentioned character, formed of few and simple parts, which are inexpensive to manufacture and may be quickly and easily assembled and separated.

20 Other objects and advantages of the invention will be apparent during the course of the following description.

In the accompanying drawings forming a part of this specification and in which like numerals are employed to designate like parts throughout the same, Figure 1 is a central vertical sectional view through a burner embodying our invention, taken on line 2--2 of Fig. 2, and, Fig. 2 is a plan view of the same with parts removed.

25 In the drawings, wherein for the purpose of illustration is shown a preferred embodiment of our invention, the numeral 5 designates a main shell or body portion of the burner, having an annular interior combustion chamber 6, as shown. The body portion 5 is provided with an inner air inlet opening 7 and with outer air inlet openings 8, oppositely arranged, whereby air passes 30 into the annular combustion chamber 6 in opposite directions, as indicated by the arrows, for a purpose to be more fully explained. The body portion 5 is provided with a flange 9, whereby the same may be 35 supported or suspended, as is customary.

The numeral 10 designates a heating plate, which is preferably circular and curved in vertical cross-section, as shown. This heating plate is supported in spaced 40 relation from the body portion 5 by depending legs 11, preferably cast integral therewith, and provided upon their outer sides with openings or notches 12, to receive the wall or edge of the opening 7, such wall being provided with a corresponding number 45 of openings or notches 13, adapted for regis-

tration with the openings 12, whereby the legs 11 may be inserted within the opening 7, and subsequently turned whereby they are supported by the edge or wall of the opening 7, as is obvious. It is thus seen that simple and reliable means are provided for detachably securing the heating plate 10 to the body portion 5, allowing the same to be readily separated and assembled.

50 The heating plate 10 is provided upon its upper surface with spacing lugs 14, which engage and hold a cap 15 in spaced relation from the heating plate 10, as shown. The cap 15 is provided with a depending annular flange 16, spaced from the edge or periphery of the heating plate 10, as shown. The cap 15 forms with the heating plate 10 a vaporizing chamber 17, discharging downwardly at the extremity of the flange 16, into the 55 annular combustion chamber 6, whereby the vaporized kerosene oil is introduced into approximately the central portion of the annular combustion chamber 6 between and in the presence of the oppositely entering streams of air, whereby the combustion of the vaporized oil is complete to a high degree.

60 The numeral 18 designates a fuel supply pipe, through which the kerosene oil or the like passes, the same being fed by gravity, pressure or the like. This pipe may be provided with a control or cut-off valve (not shown). The pipe 18 leads into a coupling 19, arranged within an opening 20 formed 65 through the central portion of the heating plate 10, as shown. It is obvious that the pipe 18 supplies the oil to the upper surface 70 of the heating plate 10 at the center thereof.

65 In operation, the oil passes through the pipe 18 onto the heating plate 10, and will at first flow from the same at the extremity of the flange 16. This oil may be ignited. As the burner begins to operate the heat from the burning oil is transmitted to the 75 heating plate 10, whereby such heating plate vaporizes the oil traveling outwardly through the vaporizing chamber 17. This vaporized oil now discharges at the extremity of the flange 16 into the approximately 80 central portion of the combustion chamber 6, between and in the presence of the oppositely traveling incoming streams of air. The vaporized oil is thus intimately mixed with the air, to carburet the same, producing 85 a gas which is highly economical in use.

90 It is to be understood that the form of our

invention herewith shown and described is to be taken as a preferred example of the same, and that various changes in the shape, size, and arrangement of parts may be resorted to without departing from the spirit of the invention or the scope of the subjoined claims.

Having described the invention, we claim:

- 10 1. A burner of the character described, comprising a main shell having an approximately annular combustion chamber having its outer and inner walls provided with oppositely arranged air inlet openings, a heating plate arranged within the approximately annular combustion chamber and provided with supporting means engaging the inner wall of the main shell to maintain the same spaced therefrom, and a cap arranged upon and spaced from the heating plate to form therewith a vaporizing chamber discharging toward the combustion chamber.
- 15 2. A burner of the character described, comprising a main shell having an approximately annular combustion chamber provided upon its inner and outer walls with oppositely arranged air inlet openings, a heating plate arranged within the approximately annular combustion chamber and having its upper surface inclined toward the outer edge thereof, means for supporting the heating plate in spaced relation from the inner wall of the main shell, a cap arranged upon and spaced from the heating plate to form therewith a vaporizing chamber discharging toward the combustion chamber, and means to supply a liquid fuel to the upper inclined surface of the heating plate at a point near the center thereof.
- 20 3. A burner of the character described, comprising a main shell having an approximately annular combustion chamber provided upon its inner and outer walls with oppositely arranged air inlet openings, a

heating plate arranged within the approximately annular combustion chamber and having its upper surface inclined toward its outer edge and provided with an approximately centrally arranged aperture, means for feeding a liquid fuel upwardly through the approximately centrally arranged aperture to supply the same to the upper inclined surface of the heating plate, and a cap arranged upon and spaced from the heating plate to form therewith a vaporizing chamber and provided at its periphery with a depending flange to deflect the vaporized liquid fuel downwardly into the combustion chamber between and in proximity to the oppositely traveling incoming streams of air.

4. A burner of the character described, comprising a main shell having an approximately annular combustion chamber provided upon its inner wall with an air inlet opening having its wall provided with a plurality of notches and upon its outer wall with a plurality of air outlet openings oppositely arranged with respect to the air inlet opening of the inner wall, a heating plate arranged within the approximately annular combustion chamber and carrying depending legs provided upon their outer sides with notches to coöperate with the first named notches, spacing lugs formed upon the upper surface of the heating plate, a cap arranged upon the spacing lugs and forming with the heating plate a vaporizing chamber, and means to supply the liquid fuel to the vaporizing chamber.

In testimony whereof we affix our signatures in presence of two witnesses.

HARRY V. DRESBACH.
WILLIAM O. DRESBACH.
